UNITED STATES PATENT OFFICE.

JOHN MASON, OF FRANCESVILLE, INDIANA.

GRAIN-BIN.

SPECIFICATION forming part of Letters Patent No. 322,305, dated July 14, 1885.

Application filed April 16, 1885. (No model.)

To all whom it may concern:

Be it known that I, JOHN MASON, a citizen of the United States, residing at Francesville, Pulaski county, Indiana, have invented new 5 and useful Improvements in Grain-Bins, of which the following is a specification.

The object of my invention is to provide a convenient and inexpensive grain-bin adapted more especially for the use of farmers and 10 small retail dealers, and so arranged as to afford ready access to the bin through a drop-door on one side or in its front, while the contents of the bin are effectively protected from the ravages of rats, mice, and other vermin.

15 In the annexed drawings, illustrating the invention, Figure 1 is a perspective view of my improved grain-bin, and Fig. 2 is a sectional elevation of the same.

The bin is composed of a rectangular frame 20 consisting of the uprights A A and cross-girts B B, and is provided with an elevated wood floor, C, and a top and sides that are formed of continuous sheets of wire-gauze. I prefer to place the bottom or floor C of the bin about 25 twelve inches above the lower ends of the uprights A A, to which said floor is secured, the lower ends of the uprights thus serving as legs a a for supporting the bin. The cross-girts B B may be formed with rabbets b b, if desired, 30 for supporting horizontal partitions or shelves, as D, and the interior of the bin may also be divided by one or more vertical partitions, as E, thus affording storage-room for several varieties of grain within one cover.

35 The sides of the bin, as F, are composed of a continuous sheet of wire-gauze extended around the outer sides of the uprights A and girts B, the ends of the gauze-cloth being made to overlap at one corner of the bin or other 40 convenient point, while its lower edge is folded or turned over beneath the floor of the bin. The top G is also composed of wire-gauze cloth, and is made in one piece of sufficient size to be turned down over the upper edges 45 of the side covering. I thus avoid all open joints that would be liable to permit the entrance of vermin.

In the front or on one side of the bin is a drop-door, H, that extends entirely across the bin, and is hinged by its lower edge to one of 50 the cross-girts, a suitable fastening, K, being provided at the top. It will be observed that the door H is arranged at some distance above the floor of the bin, so that when opened it will hang vertically in front of and parallel 55 with the side of the bin without being in the way. This construction also prevents the grain at the bottom of the bin from falling out when the door is opened. The door H is covered on the outside with wire-gauze, like the 60 top and sides of the bin. The wire-gauze covering should be of fine mesh, and being stretched around the exterior of the bin, to which it may be closely riveted or otherwise 65 securely attached, affords, as will be seen, a protection to the wooden portion of the frame.

By employing galvanized wire-cloth all liability of rust and corrosion from the moisture in the grain will be avoided.

It is obvious that a grain-bin of this construction will afford complete protection against the attack of rats, mice, and other vermin, while at the same time it allows the free escape of heat and moisture from the grain, and furnishes the necessary ventilation, all of 75 which is accomplished at slight expense.

What I claim is—

1. The herein-described grain-bin, consisting of a rectangular frame having an elevated wooden floor and covered on the sides and 80 top with wire-gauze, said bin being provided with a drop-door, substantially as described.
2. In a grain-bin, the combination of the uprights A A, girts B B, wire-gauze covering F G, wooden floor C, and a wire-gauze-covered door, H, adapted to swing downward, substantially as described.

In testimony whereof I affix my signature in presence of two witnesses.

JOHN MASON.
